UNITED STATES PATENT OFFICE.

JOSEPH J. LINEHAN, OF WHITE PLAINS, NEW YORK.

SPRINKLER-HEAD.

1,241,747.

Specification of Letters Patent. Patented Oct. 2, 1917.

Application filed February 17, 1916. Serial No. 78,954.

To all whom it may concern:

Be it known that I, JOSEPH J. LINEHAN, a citizen of the United States, residing at White Plains, in the county of Westchester, 5 State of New York, have invented certain new and useful Improvements in Sprinkler-Heads; and I do hereby declare the following to be a full, clear, and exact description of the invention, such as will enable others 10 skilled in the art to which it appertains to make and use the same.

The present invention is directed to improvements in sprinkler heads, used in connection with automatic fire extinguishing 15 systems.

The invention has for its object to provide a sprinkler head which is so constructed that upon being subjected to a sufficient degree of heat, it will operate to discharge water into 20 the flames.

A further object of the invention is to provide a sprinkler head which can be used exteriorly of a building in extremely cold weather without the danger of the supply 25 pipes becoming frozen.

With these and other objects in view, this invention resides in the novel features of construction, formation, combination and arrangement of parts to be hereinafter more 30 fully described, claimed and illustrated in the accompanying drawing, in which:—

Figure 1 is a front elevation of the device.

Fig. 2 is a vertical central sectional view through the same.

Fig. 3 is a bottom plan view.

Fig. 4 is a side view.

Fig. 5 is a sectional view on line 5—5 of Fig. 1.

Fig. 6 is a sectional view on line 6—6 of Fig. 1.

Referring to the drawing 1 indicates a cylindrical casing which is interiorly threaded, as at 2 for receiving the lower end of the branch pipe 3, said pipe depending from 45 the service pipe, (not shown).

The lower end of the pipe 3 constitutes a valve seat 4.

Formed integral with the casing 1 is a depending U-shaped yoke 5, the bight of which is provided with a threaded opening 6 in which is adjustably mounted a screw 7, the upper end of which being provided with a flat disk 8, while the lower end is squared, as at 9 for engagement with a tool for conveniently adjusting the screw.

Operable in the casing 1 is a conical valve

10 having an annular shoulder 11 carried thereby for supporting the gasket 12, which normally engages the seat 4 to tightly close the lower end of the pipe 3, thus insuring a 60 fluid tight joint. The valve is held normally seated by the fusible block 13 which is placed with its lower end on the disk 8 and its upper end engaged with the bottom of said valve. 65

The screw is adjustable so that the block will hold the valve tightly seated. The blocks 13 are formed preferably from sealing wax or the like when used in buildings not abnormally heated, but should the heads 70 be located in boiler rooms, or places which are abnormally heated, the blocks will be made from material which will not fuse until subjected to a great degree of heat.

The valve 10 is provided with a recess 14 75 in which is secured a contact plate 15, said plate being suitably insulated from the valve and has attached to the binding screw 16 a conducting wire 17, which leads from any suitable source of electrical energy. 80

One arm of the yoke 5 is recessed, as at 18 and has fixed therein a resilient contact strip 19, said strip having leading thereto a circuit wire 20, which is also in circuit with a suitable supply of electrical energy. 85

The valve 10, as above stated, is held in its closed position by the block 13, but should a fire occur near the device, it is obvious that the block 13 will melt, thus permitting the valve 10 to drop, and as it 90 drops the plate 16 will contact with the strip 19, thus closing the circuit and sounding an alarm, and it will be of course understood that as soon as the valve drops the water will be released and will flow against 95 the valve, which is conical, thereby spraying the same so as to extinguish the fire. It will be noted that the valve is of such height that after the block is melted the lower end of the valve will rest on the disk 100 8, while the upper end thereof will extend slightly into the casing, thus preventing the valve from tilting and dropping from the yoke 5. Thus it will be seen that the valve will always remain within the casing and 105 can be readily seated upon applying another block 13.

In instances where the sprinkler heads are exposed to extremely cold weather, it is deemed advisable that the service pipe and 110 branch pipes 3 be charged with air under pressure so that water will not enter the

2
pipes until the valve is released, thereby eliminating any danger of water freezing in the pipes and preventing the devices from operating.

5 It will be of course understood that any number of these devices may be placed in a room or other part of the building as deemed advisable.

10 The wires 17 and 20 are preferably in circuit with an annunciator, whereby it can be readily determined which sprinkler head is in operation so that the place of fire can be readily ascertained.

15 It is obvious that the disk 8 may be adjusted so that it will engage the lower end of the valve 10 so as to hold the same seated after the fusible block 13 has been removed or melted. Thus it will be seen that any one of the sprinkler heads can be shut off 20 without interfering with the operation of the remaining ones.

What is claimed is:—

A sprinkler head comprising a casing

provided with a depending yoke having a recess in one of the side members thereof, a 25 valve movable longitudinally in said casing and engageable with the inner surfaces of said side members, means adjustably carried by the bight portion of said yoke for supporting a fusible block in engagement 30 with said valve whereby the same is normally retained in its closed position, a counter sunk contact plate carried by said valve, a second contact plate mounted in the recess formed in the side member of said 35 yoke and having a portion thereof in the path of movement of said valve and adapted to be engaged by the first named contact plate to close a circuit when said fusible block is melted. 40

In testimony whereof, I affix my signature, in the presence of two witnesses.

JOSEPH J. LINEHAN.
